Primary Examiner — Messina L Smith(74) *Attorney, Agent, or Firm* — Faegre Drinker Biddle & Reath LLP(57) **CLAIM**

The ornamental design for a speaker for an automobile, as shown and described.

DESCRIPTION

FIG. 1 is a perspective view of a speaker for an automobile showing my new design;

FIG. 2 is a front view thereof; and,

FIG. 3 is a left side view thereof.

The broken lines illustrating portions of the speaker for an automobile form no part of the claimed design.

1 Claim, 3 Drawing Sheets(56)
